UNITED STATES PATENT OFFICE.

ROMAIN BOIN, OF ARGENTEUIL, FRANCE.

DYNAMO-ELECTRIC DIRECT-CURRENT GENERATOR.

Application filed October 4, 1918. Serial No. 256,845.

To whom it may concern:

Be it known that I, ROMAIN BOIN, a subject of the King of Belgians, and resident of Argenteuil, Seine et Oise, France (post-office address 22 Route de Sannois), have invented new and useful Improvements in Dynamo-Electric Direct-Current Generators, which improvements are fully set forth in the following specification.

10 The present invention has reference to direct current dynamo-electric machines; and it resides in the provision of certain improvements hereinafter fully described, relating primarily to the construction and arrangement both of the pole pieces which are comprised in the inductor in such a manner as to provide a variable gap, as well as of the armature, the object being to subject the successive members of the armature to a progressive variation of the flux.

15 In the accompanying drawings, Figures 1 and 2 are, respectively, an end view and a vertical section of the improved machine, and Fig. 3 is a view showing a modified form 25 of pole-piece.

20 Referring more particularly to the drawing, *a* indicates the shaft of the machine, *b* the inductor fixed thereto, and *c* the pole pieces. In the construction disclosed in Fig. 30 1, the pole-pieces are crescent-shaped and, by reason of that fact, produce a variable or graded air gap and, hence, a corresponding variation of the flux; but instead of being given that shape, however, they may have 35 the form represented in Fig. 3, in which their ends are tapered in width in order to obtain the desired variation of the flux, the pole-pieces themselves being arranged concentric with the armature.

40 The latter is composed of a ring or circle of members *d* disposed externally of the inductor, each member including a core *d*² surrounded by a winding *d*³, which windings are connected in series and suitably insulated. The ends or terminals of the windings are connected to the insulated segments 45 *e* of the commutator, which is engaged by the brushes *f* and, as shown, is disposed interiorly of the armature and concentric with

50 the shaft *a*. The cores *d*² lie parallel with the said shaft and are attached at one end to separate pole pieces *d*³ adjacent the inductor, and at the other end to a flux-conducting ring *d*⁴. The inductor may be magnetized either permanently or electromagnetically. Current is supplied from the

brushes *f* through conductors *f*² to slip-rings *f*³, or the like, on shaft *a*, and thence through conductors *f*⁴ to the place of use.

55 The brushes *f* are designed to travel along the commutator, as will be understood, this action being obtained, as usual, by setting up a relative rotary movement between the armature and the inductor. Either of these two companion parts may be rotated, and 60 the other part left stationary; but in the construction illustrated, it is the inductor to which the rotary movement is imparted and which, accordingly, is fixed to shaft *a* to be rotated thereby, the brushes *f* likewise being 65 connected with the shaft by means of a suitable supporting device *f*¹. During this rotation, the armature windings are subjected successively to a maximum flux of one polarity, a neutral point, a maximum flux of opposite polarity, and a second neutral point, 70 thereafter repeating the cycle.

75 The arrangement of the armature windings is such that, contrary to what is usually the case in dynamo-electric machines, where 80 the windings of sections of very different voltages cross one another and are in actual contact, the insulation of each coil from the next one is highly desirable and can readily be effected, since the windings of each coil 85 can be completely insulated from those of the adjacent coil and from the metallic parts of the machine. Relatively high voltages may thus be generated in each coil without danger of short circuits.

90 It will be apparent that the improved machine may readily be utilized as a motor, in which case the inductor, instead of being driven by means of mechanical devices, will be rotated by electric current which is supplied to the armature windings through the brushes.

95 When used as direct current generators, machines of the character described have various applications, and are especially suitable for supplying the high-tension currents required in X-ray machines of the Coolidge type.

I claim as my invention:—

100 1. In a direct current dynamo electric machine, the combination of an inductor having symmetrical, elliptical pole-pieces with a variable air gap; an armature comprising an annular assemblage of windings, and a core for each winding, said windings encircling the inductor and disposed concentrically therewith and parallel to the axis of

the machine and being connected in series; a flux-conducting ring to which the cores of the windings are attached, said ring and inductor having a common axis; a commutator having insulated segments to which the windings are attached; and brushes bearing against the commutator.

2. In a direct current dynamo electric machine, the combination of a rotary shaft; an inductor fixed to the shaft to rotate therewith and having elliptical pole-pieces with a variable air gap; a stationary armature comprising an annular assemblage of windings, and a core for each winding, said windings encircling the inductor and disposed concentrically therewith and parallel to said

shaft and being connected in series; a flux-conducting ring to which the cores of the windings are attached, said ring and inductor having a common axis; a commutator 20 having insulated segments to which the windings are attached; and brushes carried by said inductor shaft and bearing against the commutator.

In testimony whereof I have signed this 25 specification in the presence of two subscribing witnesses.

ROMAIN BOIN.
